UNITED STATES PATENT OFFICE.

EUGEN EBERLE, OF AUGSBURG, GERMANY.

PROCESS OF SUPPLYING FUELS WHICH IGNITE WITH DIFFICULTY TO INTERNAL-COMBUSTION ENGINES.

1,093,553.

Specification of Letters Patent. Patented Apr. 14, 1914.

Application filed June 17, 1913. Serial No. 774,137.

To all whom it may concern:

Be it known that I, EUGEN EBERLE, a citizen of the German Empire, and residing at Augsburg, Germany, have invented a certain new and useful Improved Process of Supplying Fuels Which Ignite with Difficulty to Internal-Combustion Engines, of which the following is a specification.

My invention relates to a process for enabling fuels such as heavy oils which ignite with difficulty, to be advantageously used in internal combustion engines of the kind in which the air and the fuel are separately compressed, as in the well-known Diesel type of engine. In some instances it has heretofore been necessary when using oils which burn with difficulty in Diesel motors, such as tar oil, tar, etc., to also employ a special easily ignited fuel to start the ignition in order to insure the combustion of the heavy oil. This use of a special fuel is troublesome and complicates the valve-gear as well as increases the cost of fuel consumption.

A primary object of my invention is to overcome the necessity of employing a special easily ignited fuel when using heavy oils, the invention being based upon the following observations and the knowledge acquired therefrom.

30 A constant quantity of combustion air is always drawn in and compressed in a Diesel motor independent of the load. The combustion of the fuel, injected toward the end of the stroke, increases the temperature. 35 With diminishing load, less fuel will be injected in the cylinder during each stroke. The smaller quantity of fuel will produce a smaller temperature increase of the combustion air. A correspondingly smaller 40 amount of heat will therefore be transmitted to the walls of the cylinder and the cover. On account of the lower temperature of the walls, the fresh air will be less heated during the compression in the working cylinder.

45 As a consequence the injected fuel, during a smaller load on the machine will come in contact with less heated air and with comparatively cold walls. Under these circumstances it will be evident, that the fuel requires longer time for evaporation, which is particularly the case with such fuels as tar oil and tar, which ignite with difficulty. In order, nevertheless, to ignite the fuel at the correct time during each different load, that 55 is at the instant the piston of the machine is

at the dead center, the influence of the lower temperature is, in the present invention, compensated for by a correspondingly earlier opening of the nozzle valve.

The quantity of the injected combustion air depends on the duration of opening and length of stroke of the valve needle. In all the usual devices the fuel valve is operated by similar cams for all different loads. In order to regulate the machine, only the necessary quantity of fuel for each stroke is changed, while the duration of opening and length of stroke of the needle valve remains constant. As a consequence, during a small load, a small quantity of fuel is injected into the cylinder with too much combustion air.

When an internal combustion engine is running under normal load the combustion air is so highly heated by the surrounding metal parts during the suction and compression strokes that the final compression temperature is so high that with the aid of the known atomizing and distributing devices even heavy oils, such as tar oil, for example, are ignited with certainty by the compressed air. When the load decreases, however, the temperature of the cylinder walls and the piston and the final temperature of the compressed air is lower than when the engine is running under normal load, so that certainty of ignition is impaired. If the time during which the fuel valve remains open is not varied with a decreasing load, the quantity of air entering the cylinder is excessive in proportion to the quantity of fuel injected and this excessive amount of air rapidly cools the atomizer and fuel nozzle owing to conduction of heat and vaporization of the fuel, so that certainty of ignition is still further impaired. This excessive amount of air also blows the fuel completely out of the nozzle and, when the next charge of fuel is supplied, insufficient time is given to this fuel to reach the seat of the nozzle valve and completely surround it; consequently, when the said valve is lifted, pure and comparatively cold injection air first reaches the cylinder and still further cools the not very hot compressed air, so that when the fuel enters the cylinder the certainty of ignition due to contact with this compressed air is further impaired. From this observation it follows that certain ignition of heavy fuels depends upon

the correctness of the ratio of the air to the fuel in the air-fuel mixture injected, and that it is important that the fuel, as far as possible unmixed with the air, should enter the cylinder immediately the valve lifts. Further observations show that it is advantageous to allow the heavy fuel more time to vaporize under light loads than under heavy.

- 10 According to my invention I take advantage of the aforesaid observations and vary both the duration of the opening of the fuel valve and the time at which such opening occurs, relative to the turning point 75
15 of the piston, viz. the upper dead center of the crank pin, in accordance with the load on the engine, while the air pressure and air supply are constant, that is to say with heavy loads the valve is opened late and 80
20 remains open for a comparatively long period of time, while with light loads the contrary is the case. The opening of the valve therefore sometimes takes place some considerable time before the piston reaches 85
25 the position in which the crank-pin is at its upper dead center. The effect of this will be readily understood from what has already been explained. The fuel valve is preferably controlled in the manner stated 90
30 by a governor.

It has been found in practice that it is not necessary to control the time at which the valve opens and the time during which the same is open in exact accordance with 95
35 the load; it suffices generally to do this in stages. For example, one may leave the distribution unaltered from full load to half load and then to vary it once only for the range of loads between half load and running light. If different cams are employed 100
40 for this purpose one of them will serve for the range of higher and the other for the range of lower loads.

The accompanying drawings serve to further explain the process.

In these drawings: Figures 1 and 2 are elevations, partly in section, showing one form of cam mechanism for carrying out my process, and Figs. 3 and 4 are similar 105
50 views showing a second form.

In Figs. 1 and 2 a device is illustrated, whereby the beginning of the early opening of the valve relative to the turning point of the piston and the duration of such opening 110
55 can be varied dependently on the load, and hence on the governor. *a* designates the cam-shaft and *b* the cam having the longitudinal projection *c*. One of the ends (in the drawing, the left end) of the projection 115
60 of this cam has a suitably curved face for raising the valve when the engine has the minimum load, and the other end a suitable face for raising the valve when the load is the maximum. As will appear more clearly 120
65 from Fig. 2, the cam surfaces at each end

of the cam are differently disposed, so that the lower cam surface, used when the engine runs light, commences earlier and ends earlier as regards a certain point on the periphery, than does the higher curve, used 70
when the engine has a heavy load. Between its two ends the cam progressively changes in form to correspond with intermediate loads. An anti-friction roller *d* on a lever *e* is actuated in the usual manner by 75
the cam, and this lever opens the fuel valve *f*. The cam *b* is slid along by the governor, whereby at each particular load the corresponding curved face of the cam bears against the roller *d*. Consequently the fuel 80
valve *f* will be opened earlier in the cycle for a light load on the engine than for a heavy one. Considering a certain point in the cycle, for instance the upper dead center of the crank pin or the turning point of the 85
piston, more oil will have been injected and heated at that particular point, when the engine is running light, than when it runs with full load.

The construction of the nozzle as illustrated in Fig. 2 and the following description thereof, forming no part of this invention, is merely introduced for the purpose of making the operation of the device 90
clearer.

The fuel valve *f* has its seat at *s* where the nozzle *r* receiving fuel and compressed air through separate conduits, is closed toward the compression chamber of the cylinder. In the nozzle are provided several 100
disks *l*, *m*, *n*, *p*, *q* with fine holes drilled in such positions, that the holes in the individual plates do not lie opposite each other. The quantity of fuel necessary for each working stroke is supplied through a fuel 105
passage *K*, which opens into the nozzle chamber above the so-called atomizing disks *l*, *m*, *n*, *p*, *q*. The fuel runs partly through the perforated disks and is distributed over the surface of these disks. The compressed 110
air enters the nozzle chamber *r* above the fuel passage. At the instant when the fuel mixture has to be injected into the cylinder, the valve *f* opens, and the higher pressure that the air, stored in the nozzle chamber *r*, 115
possesses over the pressure in the compression chamber of the cylinder, drives with great violence the fuel, which is partly adhering to the atomizing disks and partly situated above the uppermost atomizing disk *l*, through the perforations in the atomizing disks, and causes thereby an intimate intermingling of the air with the fuel. This mixture of fuel and air is then driven 120
through the fine opening *o* in the spraying disk *g*, when it attains very high velocity. When emitted from this opening in the large cylinder chamber, the comparatively 125
large fuel drops in the mixture are torn apart into very fine particles, so that a still 130

more intimate intermingling of fuel and air takes place, which is necessary for an advantageous combustion.

The injection of fuel as well as the necessary mixing of fuel and air is, in the described device evidently caused by the opening of a single valve *f*. Should the valve *f* as is the case in earlier constructions, stay open too long with a light load, admitting an excessively large quantity of air into the cylinder, the air will then sweep away all the fuel from the atomizing disks, and blow it into the cylinder. But if only so much air flows into the cylinder, as would be necessary for combustion at light load, a small quantity of fuel, so called "ignition drops," will then remain close over the valve seat, during the injection of the fuel into the cylinder, as has been indicated by the black spots *t* in Fig. 2. During the subsequent opening of the valve *f*, this small quantity of fuel, "ignition drops," enters the cylinder in advance and starts the combustion therein. If these "ignition drops" are not formed, on account of the passing in of too great a quantity of air, as has been described above, cold air will then first enter the cylinder from the space *r*¹, when the valve is opened the next time, and causes the unfavorable action for the combustion.

In Figs. 3 and 4 a device is illustrated wherein cam faces 1, 2, 3, 4, adapted only for certain loads, *e. g.* for four loads, are moved into action successively, and hence, in stages. In order that the cam *b* may be easily slid along the shaft *a* the various cam faces are connected one to another by slanting guide faces *g*, *h*, *i*, so that when the cam is axially shifted, the roller *d* slides on a guide face up or down to the next higher or lower cam face. In this case the cam can be shifted very readily by hand.

Similarly to Fig. 2, Fig. 4 clearly indicates the distributions of the different cam surfaces. Considering for instance the vertical center line in the figure as coinciding with the upper dead center of the crank

pin, it is evident that with cam surface 1 in action, almost all the fuel for the stroke has been admitted and had time to be heated before the dead center point is reached; whereas the valve is just starting to open when cam surface 4 is in action.

I claim:—

1. The process of supplying to internal combustion engines of Diesel type, mixtures containing fuels which ignite with difficulty and varying the fuel element according to the load upon the engine, which consists in delaying the commencement of fuel introduction relatively to the dead center of the engine, proportionately to the increase of load, and increasing the duration of admission as the period of introduction is delayed.

2. The process of supplying to internal combustion engines of Diesel type, mixtures containing fuels which ignite with difficulty and varying the fuel element according to the load upon the engine, which consists in delaying the commencement of fuel introduction relatively to the dead center of the engine, proportionately to the increase of load, and increasing the quantity of fuel supplied as the period of introduction is delayed.

3. The process of supplying to internal combustion engines of Diesel type, mixtures containing fuels which ignite with difficulty and varying the fuel element according to the load upon the engine while maintaining the air supply at constant pressure, which consists in delaying the commencement of fuel introduction relatively to the dead center of the engine, proportionately to the increase of load, and increasing the duration of admission as the period of introduction is delayed.

In testimony whereof, I affix my signature in the presence of two witnesses.

EUGEN EBERLE.
